[57] CLAIM

The ornamental design for the chair back attachable baby retaining article, as shown and described.

DESCRIPTION

FIG. 1 is a front, top and left side perspective view of a chair back attachable baby retaining article showing my new design;

FIG. 2 is a rear, bottom and right side perspective view;

FIG. 3 is a left side elevational view;

FIG. 4 is a front elevational view;

FIG. 5 is a sectional view taken along line 5—5 of FIG. 4; and

FIG. 6 is a view of the baby retaining article in flattened condition with the straps shown as broken for convenience of illustration.
